UNITED STATES PATENT OFFICE.

GEORGE F. ALLEN, OF ORONOGO, MISSOURI.

HYDROCARBON-OIL BURNER.

Application filed June 16, 1921. Serial No. 478,070.

To all whom it may concern:

Be it known that I, GEORGE F. ALLEN, a citizen of the United States, residing at Oronogo, in the county of Jasper and State 5 of Missouri, have invented certain new and useful Improvements in Hydrocarbon-Oil Burners; and I do hereby declare the following to be a full, clear, and exact description of the invention, such as will enable 10 others skilled in the art to which it appertains to make and use the same.

The invention relates to burners for utilizing oil as fuel, the same being atomized by a fluid medium in the form of a jet, steam 15 being preferred since it heats the oil and its pressure is utilized both as feeding and atomizing means for the fuel.

The invention insures a positive feed of the oil by creating a suction on the supply 20 and the fluid medium, air or steam, both heats and atomizes the oil, the mixture after combining being agitated to further the atomization by a stationary spiral removably fitted in the burner tip.

Other objects and advantages will be apparent and suggest themselves as the nature of the invention is understood.

While the drawings illustrate an embodiment of the invention it is to be understood 30 that in adapting the same to meet different conditions and requirements, various changes in the form, proportion and minor details of construction may be resorted to without departing from the nature of the invention.

Referring to the accompanying drawings forming a part of the specification,

Figure 1 is a side view of a burner embodying the invention, parts being broken 40 away,

Figure 2 is a central longitudinal section thereof, the valve operating means and the fluid supply being omitted,

Figure 3 is a sectional detail of the head 45 threaded to the receiving end of the body and the tube attached thereto, the parts being illustrated on a larger scale,

Figure 4 is an enlarged sectional view of the tip and the spiral located therein,

Figure 5 is a detail perspective view of the spiral, and

Figure 6 is a detail view of the delivery 50 end of the body and the gland fitted to the stuffing box thereof.

Corresponding and like parts are referred to in the following description and design-

nated in the several views of the drawings by like reference characters.

The burner comprises a body 1 which is elongated and of cylindrical form. The delivery end of the body 1 has a tapered portion 2 and a contracted portion 2^a which is externally and internally screw threaded. A head 3 is threaded to the receiving end of the body and has an axial opening 3^a and 60 a nipple 4 in line with said opening. A tube 5, centrally disposed within the body 1, is threaded to the nipple 4 and its delivery end 5^a is made conical and formed with a relatively small opening 6 constituting an outlet for a jet of steam or other fluid medium. A pipe 7 is coupled to the head 3 and is in communication with a source of fluid supply such as air or steam. A fitting 7^a connects the supply pipe 7 with the head 3. A valve 75 20 is threaded to the fitting 7^a at 21 and is provided with a wheel 22 or other type of handpiece. The valve 20 extends through the tube 5 and is adapted to close the outlet 6 or control the fluid outflow therethrough. 80

An oil pipe 8 connects with a side of the body 1 near the head 3 and supplies fuel to the burner. A short tube 9 is threaded within the contracted end 2^a of the body 1 and constitutes a regulator. The tube 9 is 85 adjustable to admit of the distance between its inner end and the delivery end of the tube 5 varying as required. A gland or nut 10, threaded on the contracted end 2^a of the body 1, serves as means for securing 90 a tight joint between the regulator 9 and the body 1. The inner end of the tube 9 is flared, as indicated at 9^a, to correspond with the conical end 5^a of the tube 5 to insure a tight joint when the tube 9 is moved in to 95 shut off the supply of fuel. The tube 9 is enlarged and provided with pins 13 to enable a firm and positive grip being obtained on the tube when turning the same to shut off the fuel or regulate the supply there- 100

of to the burner. A tube 11 is coupled to the regulator 9 and the latter has a polygonal portion 12 at its outer end to receive a wrench or spanner whereby to hold the part 9 stationary when screwing the part 11 there- 105 to. A tip 14 is connected to the outer end of the tube 11 by means of a coupling 23 and has an outlet 15 for the fuel. The outlet 15 is flared to effect delivery of the fuel in a spray or mist. The opening of the tip 14 adjacent the outlet 15 is contracted to 110 form an inner shoulder 16 which constitutes

a stop to limit the forward movement of a stationary spiral 17 removably fitted within the tip 14 and designed to impart a whirling movement to the fuel to further assist 5 vaporization thereof.

The liquid fuel or oil is supplied to the body 1 by means of the pipe 8 and surrounds the tube 5. The steam or other fluid medium is admitted to the body of the burner by 10 means of the pipe 7 and passed through the tube 5 and escapes therefrom through the outlet 6 in the form of a jet. The oil surrounding the tube 5 is heated and caused to flow freely and is more readily atomized 15 when commingling with the jet of steam at the contracted delivery end 2 of the body 1. It is also observed that the jet of steam materially assists the feeding of the oil to the body 1 by the tendency to create a suction 20 therein in a manner well understood. The delivery of the fuel may be regulated by moving the part 9 in or out thereby varying the space between the faces 5^a and 9^a through which the oil passes from the body 25 1 to the part 9. When adjusting the part 9 it is rotated by means of the pins 13. The atomized oil and steam pass through the tube 11 into the tip 14 and out through the opening 15, a whirling motion being imparted thereto by means of the spiral 17 whereby a thorough admixture of the oil 30 and steam is effected and vaporization of the fuel further assisted by the breaking up of any particles not atomized. By proper adjustment of the valve 20 the supply of steam or other fluid medium may be regulated or cut off as required. 35

What is claimed is:—

1. An oil burner comprising an elongated

body having its delivery end contracted and 40 a tapered portion adjacent the contracted end, and having a fuel inlet at its opposite end, a head fitted to the receiving end of the body, a tube within the body and spaced therefrom and attached at one end to said head, and having a jet outlet at its opposite end terminating within the tapered portion of the body, means for supplying steam to said tube, a valve within the tube, and a regulator threaded to the contracted end 45 of the body and adapted to coact with the jet outlet end of the said tube to regulate the flow of the fuel through the body. 50

2. An oil burner comprising an elongated body having its delivery end contracted and 55 internally and externally screw threaded, and having a tapered portion adjacent the contracted end, said body having a fuel inlet at its opposite end, a head applied to the receiving end of the body, a tube carried by said head and disposed within the body and terminating in a conical jet outlet within the tapered portion of the body, a fitting carried by said head and having a lateral inlet for a fluid medium, a valve 60 threaded to said fitting and adapted to control the jet outlet of said tube, a regulator threaded within the contracted end of the body and coacting with the conical jet outlet of the jet tube, and a gland threaded upon 65 the contracted end of the body. 70

In testimony whereof I affix my signature in presence of two witnesses.

GEORGE F. ALLEN.
